(57) CLAIM

I claim the ornamental design for a clothing outfit, as shown and described.

DESCRIPTION

FIG. 1 is a front perspective view of a clothing outfit showing my new design with the belt in a fastened configuration;
FIG. 2 is a front elevational view of FIG. 1;
FIG. 3 is a rear elevational view thereof, the belt omitted for clarity of illustration;

FIG. 4 is a rear elevational view of FIG. 1;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a front perspective view thereof, illustrated with the belt worn in a scarf configuration.

The broken lines showing a person in FIGS. 1 and 9 and a handkerchief in the figures depict environmental matter and form no part of the claimed design.
